UNITED STATES PATENT OFFICE.

FREDERICK C. COSEO, OF COLUMBUS, OHIO, ASSIGNOR TO THE JEFFREY MANUFACTURING COMPANY, OF COLUMBUS, OHIO, A CORPORATION OF OHIO.

BRAKE MECHANISM.

1,282,543.

Specification of Letters Patent. Patented Oct. 22, 1918.

Application filed September 28, 1916. Serial No. 122,760.

To all whom it may concern:

Be it known that I, FREDERICK C. COSEO, a citizen of the United States, residing at Columbus, in the county of Franklin and the State of Ohio, have invented certain new and useful Improvements in Brake Mechanism, of which the following is a specification, reference being had therein to the accompanying drawing.

10 The present invention relates to certain new and useful improvements in brake mechanisms adapted to be used with industrial locomotives, and especially with that class of industrial locomotives in which the 15 motive power is supplied by a single electric motor connected with the axles of the locomotive through suitable gearing.

It is commonly desirable that the motor man in charge of such locomotives should 20 connect and disconnect the couplings between the locomotive and its load, thus avoiding the employment of an assistant. To this end it is expedient that the motor man should ride at the end of the locomotive 25 next the load, and that the controlling mechanism should be equally accessible from either end of the locomotive.

One object of this invention is to provide improved retarding devices, operable from 30 either end of an industrial locomotive, which shall effectively retard the rotation of the driving wheels of said locomotive.

A further object is to provide convenient locking devices, adapted to retain such retarding devices in effective relation to the 35 moving parts of the locomotive, which may be locked from either end of the locomotive, and which can be released from the end at which they were locked, or from the opposite end as convenience may require.

The devices by which I attain these objects are fully set forth in the following specification and illustrated in the accompanying drawings of which:

45 Figure 1 is a side elevation of a locomotive equipped with my improved brake mechanism, the side frame being broken away to show the motor and brake mechanism.

50 Fig. 2 is a plan view of the locomotive illustrated in Fig. 1, the cover plates being removed.

55 Fig. 3 is a detail side view of one of the brake applying hand levers shown in working relation to its notched arc.

Fig. 4 is a plan view of the parts shown in Fig. 3.

Fig. 5 is a detail showing of certain parts shown in Fig. 3.

Fig. 6 is a detail view of the brake wheel 60 and the parts associated therewith.

Fig. 7 is an assembly of the brake mechanism detached from the other part of the locomotive.

Like numerals refer to similar parts in the several figures.

In Figs. 1 and 2 I have shown, for purpose of illustration, a locomotive having a main frame composed of the side plates 1 and 2 joined together by the cross plates 3 70 and 4 and by the end frames 5 and 6 on which are mounted the bumpers 7 and the draw bars 8. The locomotive is supported upon the rails 9 of any suitable track by the driving wheels 10 fixed to the axles 11 and 12 journaled in journal bearings 13 suitably connected with the side plates 1 and 2 of the locomotive frame.

The axles 11 and 12 are connected together by the driving chain 14 which engages the sprocket wheels 15 and 16 keyed to the axles. Fixed to the axle 11 is a nonoverhauling worm wheel 17 in driving engagement with the worm 18 of the worm shaft 19, which is connected with the armature shaft 20 of the motor 21 by a suitable shaft coupling 22, to drive the locomotive. In the locomotive here illustrated power is supplied to the motor 21 from the storage battery 23, but, it is to be understood that, this arrangement of parts is immaterial to the spirit of the present invention, and that where operating conditions will permit, any suitable method of supplying current to the motor may be employed, as by the well known trolley and trolley pole.

Mounted upon the cross plate 3 of the locomotive frame is a controller 24 by which the motor 21 is controlled. The operative parts of this controller are connected with a shaft 25 extending longitudinally of the locomotive, and supplied at each end with a hand wheel 26 affording means for the manipulation of the controller at both ends of the locomotive.

105 The motor 21 is mounted upon a suspension bracket 27 having at one end bearings 28 which engage the axle 11 and supported at the other end by a cross bar 29 from the side plates 1 and 2 of the locomotive frame.

Near one end the suspension bracket 27 is shaped to form a gear case 30 inclosing the worm wheel 17 and having suitable bearings 31 and 32 in which the worm shaft 19 is journaled. The worm shaft 19 is extended beyond the bearing 31 and to this extension is fixed a brake wheel 33 adapted to be clasped by the brake shoes 34 to retard the rotation of the worm shaft 19 and through it the axles 11 and 12 to check the movement of the locomotive. The brake shoes 34 are joined at their lower ends, and supported by the stud bolt 35 projecting from the extension 36 of the suspension bracket 27. At their upper ends the brake shoes 34 are connected by the toggle links 37 and 38 with the toggle lever 39 fixed to the shaft 40 extending longitudinally of the locomotive and journaled in suitable apertures of the cross plates 3 and 4. At each end of the shaft 40 is provided an operating device by which the shaft may be rotated to engage or disengage the brake shoes 34 with the brake wheel 33. As these operating devices are alike a description of one will apply to both. Fixed at the end of the shaft 40 adjacent the cross plate 3 is a hub 41 having a lateral extension 42 upon the face of which is formed a lug 43 which is engaged by the fork 44 of the hand lever 45. A hinge bolt 46 connects the lever 45 to the lug 43 for limited rotation in a plane longitudinal of the shaft 40. A compression spring 47, interposed between the extension 42 and the lever 45, tends to force them apart and an extension 48 of the fork 44 serves to limit the outward motion of the lever 45. Formed on the lever 45 is a knife edge flange 49 adapted to engage the notches 50 of the arcuate angle bar 51 attached to the cross plate 3 concentric with the shaft 40. By this arrangement the shaft 40 may be rotated, by pressure applied to the hand lever 45, to cause the brake shoes 34 to engage the brake wheel 33. When the shaft 40 has made a sufficient rotation to produce the desired pressure on the brake shoes 34, the hand lever 45 will be pressed forward until the knife edge 49 engages one of the notches 50 of the arc 51 to prevent rotation in the reverse direction and maintain the pressure upon the brake shoes. If now it is desired to release the brake from the opposite end of the locomotive it will only be necessary to apply a rotative force in the brake applying direction upon the hand lever 45 at that end of the locomotive to allow the disengagement of the knife edge 49 from the arc 51 when the spring 47 will force the lever 45 to its outer, or free position, leaving the shaft 40 free to rotate to release the brake.

What I claim is.

1. In a brake mechanism, the combination with a locomotive of the class described, of 65 brake devices associated with the propelling mechanism, and brake controlling devices at both ends of the locomotive by which the retarding effect of the brake devices may be applied and retained, said brake controlling 70 devices being releasable from either end of the locomotive.

2. In a brake mechanism, the combination with a locomotive of the class described, of 75 brake devices associated with the propelling mechanism of the locomotive, a shaft extending longitudinally of the locomotive and connected with the brake devices, a plurality of levers mounted upon the shaft to rotate it to apply the retarding effect of the 80 brake devices, means for locking each lever to prevent the rotation of the shaft in the brake releasing direction, and means for releasing the locking means by a movement of either lever.

3. In a brake mechanism, the combination with rotative power devices including a 90 drum, of brake devices associated with the drum, a shaft connected with the brake devices, a plurality of levers mounted upon the 95 shaft by which it may be rotated to apply the retarding effect of the brake devices to the drum, means for locking each lever to prevent the rotation of the shaft in a brake releasing direction and means for releasing 100 the locking means by the movement of either lever.

4. In a brake mechanism the combination with a locomotive of the class described, an 105 electric motor having its armature shaft extending longitudinally of the locomotive and connected to the axle through worm gearing, a brake drum connected to the armature shaft, brake shoes adapted to engage the drum, and a shaft extending longitudinally 110 of the locomotive by the rotation of which the brake shoes may be controlled.

5. In a brake mechanism the combination with a locomotive of the class described, an 115 electric motor having its armature shaft extending longitudinally of the locomotive and connected to the axle through worm gearing, a brake drum connected to the armature shaft, brake shoes adapted to engage the drum, and a shaft extending from end 115 to end of the locomotive by the rotation of which the brake shoes may be controlled from both ends of the locomotive.

In testimony whereof I affix my signature, in the presence of two witnesses.

FREDERICK C. COSEO.
